UNITED STATES PATENT OFFICE.

CARL W. HODGSON, OF CHICAGO, ILLINOIS.

MIXING MACHINE.

Application filed April 25, 1924. Serial No. 708,842.

To all whom it may concern:

Be it known that I, CARL W. HODGSON, a citizen of the United States, residing at Chicago, in the county of Cook and State of

Illinois, have invented certain new and useful Improvements in Mixing Machines, of which the following is a specification.

This invention relates to improvements in mixing machines particularly adapted though not necessarily limited in its use for mixing concrete, and one of the objects of the invention is to provide an improved machine of this character in which the materials to be mixed will be supplied in the proper proportions.

A further object is to provide an improved machine of this character embodying means for continuously feeding and distributing the mixed material to the road bed in such a manner that the line of work will be substantially uniform throughout substantially the range of operation of the machine.

A further object is to provide an improved machine of this character which will be of a comparatively simple, durable and compact construction and effective and efficient in operation.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a view in side elevation, partly broken away, of a machine of this character constructed in accordance with the principles of this invention.

Figure 2 is a top plan view as taken on line 2—2, Figure 1.

Figure 3 is a vertical sectional view taken on line 3—3, Figure 1.

Figure 4 is an irregular sectional view taken on line 4—4, Figure 1.

Figure 5 is a detail sectional view taken on line 5—5, Figure 4.

Figure 6 is a detail sectional view taken on line 6—6, Figure 3.

Referring more particularly to the drawings the numeral 10 designates a supporting structure which may be of any desired construction and is mounted upon wheels 11—12. Interposed between the frame 10 and the wheels 12 is a turn-table 13 of any

desired configuration by means of which the vehicle may be steered during transportation in any well known and suitable manner (not shown).

A supplemental frame or supporting structure 14 is mounted upon the structure 10 and is preferably pivotally connected thereto by means of a king pin or bolt 15, and a turntable 16 of the ordinary and well-known construction may be interposed between the two so as to permit the frame 14 to swing readily about the king pin 15 and upon the frame or supporting structure 10. The pivot thus formed is preferably arranged adjacent one end of the supplemental frame 14 and adjacent one end of the supporting structure 10. The other end of the supplemental frame 14 may be supported in any suitable manner such as by means of angle irons 17 (see particularly Figure 6), which travel upon suitable rollers 18 mounted upon an arc shaped plate 19 carried by the supporting structure 10. The plate 19 may be of any desired length but preferably substantially equal to the length of the axle 20 to which the wheels 11 are connected.

When the supplemental frame 14 is swung about its pivot 15 it will be manifest that it will be guided by the rollers 18. Any suitable means may be provided for thus swinging the frame 14. A suitable and efficient means embodies a rack shaped member 21 preferably mounted upon the supporting structure 10. A pinion 22 journaled in a suitable bearing 23 carried by the supplemental frame 14 engages the rack 21 and the pinion may be operated by means of a beveled gear 24 which meshes with a beveled gear 25 carried by a shaft, and to which shaft is connected a crank handle 26, so that by the operation of the handle 26 motion will be imparted to the gear 22 and inasmuch as this gear is carried by the swinging frame 14 and meshes with the rack 21 which is carried by the stationary frame 10, the frame 14 will be swung in one direction or the other according to the direction of rotation of the crank handle 26.

Carried by the supplemental frame 14 is a mixing chamber or receptacle 27 of any desired configuration and constructed of any suitable material. This chamber is open at the top and is provided with a discharge opening 28 through its bottom adjacent the forward end thereof. The chamber may be of any desired length and journaled therein

to extend lengthwise thereof are spaced parallel shafts 29—30, journaled in suitable bearings. Connected respectively with the shafts 29—30 to rotate therewith are a plurality of spirally shaped agitator and conveyor elements 31—32. These elements are spaced from each other in directions longitudinally of the respective shafts, and work in opposition to each other so as to insure a complete and thorough mixture of the material and also insures a rapid forward movement of the mixture within the chamber 27, when the shafts are operated. These elements 31—32 are preferably arranged in staggered relation so that when the material is delivered by one of the agitators it will be picked up by the opposing agitator, causing the material to be passed forwardly and backwardly during its travel through the chamber 27. Motion may be imparted to the shafts 29—30 in any desired or suitable manner but preferably from a motor 33 mounted upon a suitable platform 34 carried by the supplemental frame 14. The motor is preferably located adjacent the pivot 15. Operating from the motor shaft is a train of gears designated generally by the reference numeral 35 to impart motion to a shaft 36, which latter is journaled in suitable bearings and is provided with a sprocket wheel 37 for rotation therewith. The end of the shaft 29 preferably projects beyond the chamber 27. Connected with this shaft is a sprocket wheel 38 and a sprocket chain 39 passes over the sprockets 37 and 38 for operatively connecting the shaft 36 with the shaft 29. The other end of the shaft 29 preferably projects through the other end of the chamber 27 and has connected with it for rotation therewith, a gear 40 which meshes with a gear 41 secured for rotation with the shaft 29, so that when the motor 33 is operated and the shaft 36 is driven, the motion of the shaft 36 will be imparted to the shaft 30 through sprocket wheels 37—38 and sprocket chain 39. The motion of the shaft 30 will be imparted to the shaft 29 through the medium of the connecting gears 40—41.

Disposed upon the supplemental frame 14 and below the chamber 27 is another mixing chamber 42, which may also be of any desired size, length and configuration. The inner end of the chamber 42 is disposed beneath the outlet opening 28 of the chamber 27 and the chamber 42 is mounted upon suitable rollers 43 which travel upon the supplemental frame 14. In order to guide the rollers 43 in their movement upon the supplemental frame 14, the latter may be of angle iron formation as shown more clearly in Figure 3.

There may be provided angle irons 44 which depend below the chamber 42 which co-operate with the angle irons of the sup-

porting frame 14 for holding the chamber 42 against lateral displacement with respect to the supplemental frame 14.

Journaled within the chamber 42 are shafts 45—46 and these shafts have respectively secured thereto to rotate therewith a plurality of spirally shaped agitator and conveyor elements 47—48. These elements are spaced from each other in directions longitudinally of the respective shafts so as to insure a complete and thorough mixture of the material within the chamber 42, and as the material is advanced therethrough the elements 47 and 48 are preferably arranged in staggered relation so as to alternately pass the material back and forth from one set of agitators to the other. The chamber 42 is provided with a discharge outlet opening 49, to which may be connected a suitable spout 50 for delivering the material upon the road bed.

Motion is imparted to the agitator elements 47—48 in any suitable manner preferably from the shaft 36 driven by the motor 33. To that end there may be provided a sprocket wheel 51 secured to the shaft 36 and a sprocket wheel 52 secured to the end of the shaft 46, and which latter projects beyond the end of the chamber 42. A sprocket chain 53 passes over the sprockets 51 and 52, and the sprocket 52 is keyed or splined upon the end of the shaft 46 in such a manner that the shaft 46 and the sprocket 52 may be moved one with relation to the other in a direction lengthwise of the axis of the shaft 46 so as to permit the chamber 42 to be bodily moved forwardly and backwardly in a direction lengthwise of the chamber, while the sprocket 52 remains in a fixed position so as not to interfere with the driving connection between the shaft 36 and the shaft 46.

The other end of the shaft 46 preferably projects beyond the forward end of the chamber 42 and connected with such end of the shaft for rotation therewith is a gear 54, which meshes with a gear 55 secured to the shaft 45 for rotation therewith. It will thus be seen that when the shaft 36 is rotated its motion will be imparted to the shaft 46 through the chain and sprocket connections 51, 52 and 53 and the motion of the shaft 46 will be imparted to the shaft 45 through the medium of the intermeshing gears 54—55.

It is one of the objects of the present invention to maintain the discharge spout 50 as nearly as possible in such a position that when the supporting frame 14 is swung about its pivot 15 the material delivered to the road bed will be in substantially the same line. That is the end of the work will be substantially straight across the road bed. In order to accomplish this result, it is necessary that the varying movement caused by

the pivotal action of the frame 14 about the pivot 15 shall be compensated by the position of the spout or delivery outlet 50. This is accomplished by causing the chamber 42 to move longitudinally upon the supplemental frame 14 as the latter is swung about its pivot. When the frame 14 is moved in one direction the chamber 42 will move outwardly upon the frame 14 and when the frame 14 is moved in the opposite direction the chamber will move inwardly. The sliding connection between the sprocket wheel 52 and the end of the shaft 46 will permit of such a movement of the chamber 42 without interfering with the driving connection.

Any suitable means may be provided for thus shifting the chamber 42 upon the frame 14. A suitable and efficient means for automatically accomplishing this result consists 20 of a bar or member 56 which extends across the chamber 42 and is spaced thereabove. The member 56 may be supported by suitable posts 57 suitably braced as at 58.

Carried by the chamber 42 and projecting 25 thereabove preferably by being journaled upon cross members 59—60, are rollers 61—62. These rollers co-operate with the member 56 and move thereagainst. Assuming the parts to be in the position shown in

30 Figure 2, it will be noted that there is a space between the rollers 61 and 62 somewhat greater than the width of the member 56. As the frame 14 is swung about its pivot from the full line position, the roller 62 will 35 engage the cross member 56 and will cause the chamber 42 to be shifted longitudinally upon the frame 14 until the chamber 42 assumes the positions, according to the direction of movement of the frame, shown in dotted lines in Figure 2. It will be noted, 40 that the dotted line position of these chambers indicate the chamber 42 projected with respect to its full line position shown in Figure 2. From the dotted line positions, 45 when the frame 14 is swung about its pivot in the opposite direction to retract the frame 14 back to its normal position, the roller 61 will engage the member 56 and the roller 62 will move out of engagement therewith so

50 that when the frame 14 is swung about its pivot, the roller 61 will travel over the member 56 and draw the chamber 42 back to its normal position upon the supplemental frame 14.

55 With this construction it will be manifest that the material will be delivered throughout the entire area of the swinging movement of the frame 14.

It will also be manifest that there will be 60 a continuous discharge of the material through the spout 50.

Supported in any suitable manner from the frame 14 is a hopper 63 for containing the material to be mixed. This hopper is 65 preferably divided by means of partitions

64 and 65 into three chambers 66, 67 and 68. The outlets of these chambers 66, 67 and 68 communicate and discharge into the chamber 27. The chambers are arranged in accordance with the proportions of the materials to be supplied, that is to say, the chamber 66 for containing the rock will be larger than the chamber 68 for containing the sand and the chamber 67 will be smaller than the other two chambers, when concrete is being 70 handled. Arranged in the bottom of each of the chambers 66, 67 and 68 is an endless conveyor 69 having a plurality of flights 70 projecting thereabove. One of the runs of the conveyor operates within the chamber 80 adjacent its discharge outlet and passes through a suitable opening 71 in the wall of the chamber. A guard or shield 72 is provided for preventing the material from passing out of the opening 71. A rotatable member 73 having a series of blades 74 is provided adjacent the discharge outlet of the chamber. The blades 74 are so arranged that when the element 73 is rotated the blades will successively engage the flights 70 on the 85 conveyor 69 and operate the latter. This will cause the material to be fed uniformly and positively from the hopper into the chamber 27.

The rotatable member 73 shown in Figures 4 and 5, is of a size to correspond or properly handle the material to be fed thereby. A rotatable member 75 of a somewhat different construction is provided for handling the rock from the chamber 66, but 90 operates in the same manner in connection with the corresponding endless flexible member 76 upon which latter the flights 77 are secured. The corresponding element 78 for handling the sand also co-operates with 95 a similar endless conveyor 79, having flights 80 thereon.

It will therefore be seen that material will be simultaneously fed from the chambers 66, 67 and 68 into the chamber 27. These 110 chambers and the outlets thereof being so proportioned and the rotatable elements 73, 75 and 78 are so proportioned that the proper amount of material will be fed.

The elements 73, 75 and 78 may be rotated 115 in any desired or suitable manner but preferably from the shaft 30. To that end there may be provided a beveled gear 81 (see particularly Figures 1 and 2) on the shaft 30 which meshes with a beveled gear 82 120 on a shaft 83. The shaft 83 is journaled in suitable bearings 84 and has connected with it a sprocket wheel 85 over which a sprocket chain 86 passes. A sprocket wheel 87 is secured to the shaft 88 upon which all 125 of the rotatable members 73, 75 and 78 are mounted.

The material is mixed in a dry condition in the chamber 27 and is then discharged into the chamber 42, which is a wet mixing 130

chamber. Water may be supplied to the chamber 42 from any suitable source such as a tank 89 through the medium of flexible pipes 90 to supply pipes 91-92 arranged 5 along the walls of the chamber 42 on the inside thereof preferably adjacent the top. Nozzles 93 are connected with the pipes 91 and 92 and these nozzles are controlled by suitable valves 94. The nozzles are preferably directed in the direction of travel of the material in the chamber 42. Obviously by adjusting the valves 94 the proper amount of liquid may be supplied, and these nozzles 93 are located at any suitable or convenient point throughout the length of the 15 chamber 42.

It will be noted that the chambers 42 and 27 are arranged on an incline so that the chambers incline upwardly from the rear to 20 the forward end.

The object of so arranging these chambers is to retard to a certain extent the advancement of the material through the chambers so that a proper mixture will be 25 insured. A further advantage of arranging the wet mixing chamber 42 at such an angle is to prevent the water, which is delivered into the chamber, from flowing out of the discharge outlet 50 in advance of the 30 material. The water when it is delivered into the chamber 42 through the nozzles will have a tendency to flow by gravity down the incline or in a direction opposed to the advancing movement of the material through 35 the chamber 42. This will prevent the loss of water and will insure a complete and thorough mixing of all of the water with the material.

A suitable platform 95 hinged as at 96 and 40 supported by means of a brace 97 may be provided for the operator and located in a convenient position so that access may be had to the hopper 63.

With this improved construction it will 45 be manifest that a compact and comparatively simple apparatus will be produced which may be readily transported, and it will be further manifest that a thorough and complete mixture of the materials will 50 be produced.

By the use of this machine it is possible to place the apparatus in a position, when used for "alley work" that the discharge spout 50 will deliver material to the road bed substantially entirely across the road bed as it is swung about its pivot.

While the preferred form of the invention has been herein shown and described, it is to be understood that various changes 60 may be made in the details of construction and in the combination and arrangement of the several parts, within the scope of the claims, without departing from the spirit of this invention.

65 What is claimed as new is:-

1. An apparatus of the character described including a supporting structure, a supplemental support mounted thereupon for pivotal movement with respect thereto and in a substantially horizontal plane, two 70 mixing chambers mounted upon the supplemental support one discharging into the other, one of the said chambers being movable with and with respect to the supplemental support, the last said chamber having a delivery outlet, a combined mixer and conveyor in each of the chambers, and means for bodily moving one of the chambers with respect to the other chamber and with respect to the supplemental support when the latter is moved about its pivot. 80

2. An apparatus of the character described including a supporting structure, a supplemental support mounted thereupon for pivotal movement with respect thereto and in a substantially horizontal plane, two 85 mixing chambers mounted upon the supplemental support one discharging into the other, one of the said chambers being movable with and with respect to the supplemental support, the last said chamber having a delivery outlet, a combined mixer and conveyor in each of the chambers, and means operating to automatically project one of the chambers in a direction lengthwise of 90 its axis and with respect to the other chamber and the said supplemental support, when the latter is moved about its pivot. 95

3. An apparatus of the character described including a supporting structure mounted for pivotal movement in a substantially horizontal plane, two mixing chambers carried thereby, one of said chambers discharging into the other, said other chamber having a delivery outlet, one of the chambers being adapted to be projected in a direction lengthwise of its axis and with respect to the supporting structure and to be retracted when the latter is moved about its pivot, and means for automatically causing such projecting and retracting of the chamber with respect to the supporting structure. 100

4. An apparatus of the character described including a supporting structure mounted for pivotal movement in a substantially horizontal plane, two mixing chambers carried thereby, one of said chambers discharging into the other, said other chamber having a delivery outlet, one of the chambers being adapted to be projected in a direction lengthwise of its axis and with respect to the supporting structure and to be retracted when the latter is moved about its pivot, means for automatically causing such projecting and retracting of the chamber with respect to the supporting structure, and means for swinging the said supporting structure about its pivot. 110

65 5. An apparatus of the character described 115

including a supporting structure mounted for pivotal movement in a substantially horizontal plane, two mixing chambers carried thereby, one of said chambers discharging into the other, said other chamber having a delivery outlet, one of the chambers being adapted to be projected in a direction lengthwise of its axis and with respect to the supporting structure and to be retracted when the latter is moved about its pivot, and means for automatically causing such projecting and retracting of the chamber with respect to the supporting structure, the said chambers inclining upwardly from the feeding to the delivery ends thereof.

6. An apparatus of the character described including a supporting structure mounted for pivotal movement in a substantially horizontal plane, two mixing chambers carried thereby, one of said chambers discharging into the other, said other chamber having a delivery outlet, one of the chambers being adapted to be projected in a direction lengthwise of its axis and with respect to the supporting structure and to be retracted when the latter is moved about its pivot, means for automatically causing such projecting and retracting of the chamber with respect to the supporting structure, and means for delivering water into the last retracted chamber, at spaced points throughout the length of the chamber.

7. An apparatus of the character described including a supporting structure, means mounting the structure for pivotal movement in a substantially horizontal plane, a pair of mixing chambers mounted upon the structure, one of the chambers discharging into the other, means within each of the chambers for mixing the material, one of the chambers being adapted for bodily movement upon the supporting structure in directions lengthwise of the chamber, means controlled by the movement of the said supporting structure for causing a bodily movement of one of the chambers upon the supporting structure as the latter is moved about its pivot, and means for moving the said supporting structure about its pivot.

8. An apparatus of the character described including a supporting structure, means mounting the structure for pivotal movement in a substantially horizontal plane, a pair of mixing chambers mounted upon the structure, one of the chambers discharging into the other, opposed series of helicoids in each of the chambers for mixing the material therein, means for driving one of the series of helicoids from the other series, one of the chambers being adapted for bodily movement upon the supporting structure in directions lengthwise of the chamber, means controlled by the movement of the said supporting structure for causing a bodily movement of one of the chambers upon the sup-

porting structure as the latter is moved about its pivot, and means for moving the said supporting structure about its pivot.

9. An apparatus of the character described including a supporting structure mounted for movement in a substantially horizontal plane, two open chambers supported thereby, one of the chambers discharging into the other, a discharge spout leading from the said other chamber, means in each of the chambers for mixing the material, a hopper for the materials to be mixed, said hopper having a plurality of compartments each discharging into one of the said chambers, means including an endless traveling element adjacent the outlet of each of the compartments for conveying the material therethrough, flights on the said elements, and rotatable means also adjacent the respective outlets and co-operating with the said endless elements.

10. An apparatus of the character described including a supporting structure mounted for movement in a substantially horizontal plane, two open chambers supported thereby, one of the chambers discharging into the other, a discharge spout leading from the said other chamber, means in each of the chambers for mixing the material, a hopper for the materials to be mixed, said hopper having a plurality of compartments each discharging into one of the said chambers, means including an endless traveling element adjacent the outlet of each of the compartments for conveying the material therethrough, flights on the endless elements, and rotatable means including radially disposed arms adapted to engage the said flights on the said endless elements for imparting motion to the latter.

11. An apparatus of the character described including a supporting structure, two chambers mounted upon the structure, one of the chambers discharging into the other, mixing elements in each of the chambers for mixing the material therein, mechanism for actuating the mixing elements, said mechanism including a shaft, an actuating element connected with the shaft for rotation therewith, said shaft and element being relatively movable one with relation to the other and in directions lengthwise of the axis of the shaft, and means for bodily moving one of the said chambers with respect to the said supporting structure, whereby such relative movement of the said element and shaft will be effected.

12. An apparatus of the character described including a supporting structure mounted for pivotal movement in a substantially horizontal plane, a mixing chamber mounted thereupon for movement therewith and for bodily movement with respect thereto, mixing means in the chamber, said mixing means including a shaft, a gear keyed

upon the shaft for rotation therewith, means for driving the gear, means for bodily moving the said chamber and shaft with respect to the said structure and in directions 5 lengthwise of the axis of the shaft, and means for holding the said gear against lateral movement when the said chamber and shaft are bodily adjusted.

13. An apparatus of the character described 10 including a supporting structure mounted for pivotal movement in a substantially horizontal plane, a mixing chamber mounted thereupon for movement therewith and with respect thereto in a direction length- 15 wise of the axis of the cylinder, mixing means in the chamber, a fixed member, and means connected with the said chamber and co-operating with the said fixed member for moving the said chamber bodily and in a 20 lengthwise direction upon the said structure when the latter is moved about its pivot.

14. An apparatus of the character de- 25 scribed including a supporting structure mounted for pivotal movement in a sub- stantially horizontal plane, a mixing cham- ber mounted thereupon for movement there- with and with respect thereto in a direction

lengthwise of the axis of the chamber, mix- 30 ing means in the chamber, a fixed member, means connected with the said chamber and co-operating with the said fixed member for moving the said chamber bodily and in a lengthwise direction upon the said struc- 35 ture when the latter is moved about its pivot, and means for swinging the said sup- porting structure about its pivot at will.

15. An apparatus of the character de- 40 scribed including a supporting structure mounted for pivotal movement in a sub- stantially horizontal plane, a mixing cham- 45 ber mounted thereupon for movement there- with and with respect thereto in a direction lengthwise of the axis of the chamber, mix- ing means in the chamber, a fixed member, and rollers connected with the said chamber and adapted to co-operate with the said fixed member for moving the said chamber bodily in a lengthwise direction upon the support- 50 ing structure when the latter is moved about its pivot.

In testimony whereof I have signed my name to this specification on this 19th day of April, A. D. 1924.

CARL W. HODGSON.
